UNITED STATES PATENT OFFICE.

NEFF E. PARISH, OF READING, PENNSYLVANIA, ASSIGNOR TO PARISH MANUFACTURING COMPANY, OF READING, PENNSYLVANIA, A CORPORATION OF NEW JERSEY.

HYDRAULIC PRESS.

1,002,747.

Specification of Letters Patent.

Patented Sept. 5, 1911.

Application filed January 19, 1911. Serial No. 603,418.

To all whom it may concern:

Be it known that I, NEFF E. PARISH, citizen of the United States, residing at Reading, in the county of Berks and State of Pennsylvania, have invented certain new and useful Improvements in Hydraulic Presses, of which the following is a specification.

This invention relates to improvements in hydraulic presses and the object is to provide a press for forming channel irons.

The invention consists of an arrangement of press units of any desirable number, which units are identical in construction and 15 which work in unison.

The invention comprises a press in which two vertically moving rams are employed, one of which moves up and the other down and between which the channel is formed by 20 first gripping the plate along its longitudinal center and while so held, forming the channel by pressing up the longitudinal edges thereof. With this construction of press the channel bed is first pressed perfectly flat, removing any irregularities in 25 this portion of the plate and allowing it to retain its proper shape during the pressing up of the sides.

The invention is more fully described in 30 the following specification and clearly illustrated in the accompanying drawing, in which:

Figure 1 is a side elevation, showing two of the press units. Fig. 2 is a vertical sectional view of one of the press units showing a plate in position ready to be operated upon. Fig. 3 is a plan view of one of the press units. Fig. 4 is an enlarged section on line X—X of Fig. 2.

40 The numeral 1 designates the base and 2 the main frame member of the press. The upper section of the frame 3, is joined to the main portion by means of side uprights 4.

In each of the frame sections is formed a 45 cylinder 5 having suitable hydraulic connections 6, and each of the cylinders is provided with a ram 7 adapted to move therein by the hydraulic action, in the usual manner of hydraulic presses. The upper rams 7 carry a beam 8 to the under face of which is secured the male die member 9. This beam, as shown in Fig. 1, is backed by the rams 7 in the entire series of press units, and it moves 50 in guides 10 secured to the upper frame sec-

tions. The lower rams 7 carry a movable 55 platen 11 which travels between and is guided by the uprights 4. This platen 11 is formed with a central opening through which a clamping block support 12 passes. This support rests on the frame section 2 and 60 is rigid. On the top of this support is placed the clamping block 13, between which and the male die 9 the plate 15 is held while the channel is formed therefrom.

The numeral 14 designates the female die 65 members, which are located in a central depression in the platen 11 and are held in position by means of liners 16.

When the channel is to be formed, the plate 15 is placed across the female dies as 70 shown in Fig. 2. The upper ram is started and the beam is lowered until the male die 9 rests upon and firmly holds the plate against the clamping block 13. This action will remove all unevenness from the central 75 portion of the plate and hold it perfectly flat during the following step of the operation.

When the plate is so secured, the lower ram is started. As this moves up, carrying with it the platen and the dies 14, the side 80 walls of the channel are formed by pressing up the longitudinal edges of the plate. The central portion of the plate is firmly held during this latter step, between the male die and the clamping block on the rigid support 12.

It is evident that with this press, the channel when formed will have a perfectly even base as there is no possibility of its bending during the upward movement of the dies. 90

It is evident also that the dies may be changed to suit various shapes of channels to be formed, and that any number of press units may be employed, depending on the length of the channel to be bent. 95

Having thus fully described my invention, what I claim and desire to secure by Letters Patent is:—

In a hydraulic press, a plurality of press units each comprising a frame, an upper and lower cylinder, vertically movable rams for said cylinders adapted to move toward each other, a beam carried by the upper rams, a male die member on the under face of the beam, guides for the beam, a platen carried 100 by the lower rams, guides for the platen, removable female die members located in the upper face of the platen, retaining liners 105

for the die members in the platen, a clamping block, a rigid support for the clamping block, said block being in vertical alinement with the male die member and adapted to 5 grasp between its upper face and the male die member a sheet of metal, means for lowering the upper rams until the sheet of metal is secured between the male die member and the clamping block, and means for raising

the lower rams and female die members 10 while the sheet is so held.

In testimony whereof I affix my signature, in presence of two witnesses.

NEFF E. PARISH.
